(57) **CLAIM**

The ornamental design for a component for a cell-collecting cartridge, as shown and described.

DESCRIPTION

FIG. 1 is a front view of a component for a cell-collecting cartridge of the present invention.

FIG. 2 is a rear view of the component for a cell-collecting cartridge of FIG. 1.

FIG. 3 is a left side view of the component for a cell-collecting cartridge of FIG. 1.

FIG. 4 is a right side view of the component for a cell-collecting cartridge of FIG. 1.

FIG. 5 is a top view of the component for a cell-collecting cartridge of FIG. 1.

FIG. 6 is a bottom view of the component for a cell-collecting cartridge of FIG. 1.

FIG. 7 is a perspective view of the component for a cell-collecting cartridge of FIG. 1; and,

FIG. 8 is a sectional view taken along line 8-8 of the component for a cell-collecting cartridge of FIG. 1, in which the internal components are omitted.

The whole of the portion of the component for a cell-collecting cartridge is semi-transparent. The alternate dash-dot lines in FIGS. 1 and 7 represent the bounds of the claim, and the other broken lines represent the unclaimed portions of the component for a cell-collecting cartridge. None of the broken lines form a part of the claimed design.

1 Claim, 8 Drawing Sheets
